UNITED STATES PATENT OFFICE

93,661

DESIGN FOR THE TOP PLATE OF AN AMUSEMENT AND VENDING DEVICE

Rayburn F. Kennedy, Hamilton, Ohio

Application October 9, 1933, Serial No. 49,422

Term of patent 7 years

To all whom it may concern:

Be it known that I, RAYBURN F. KENNEDY, a citizen of the United States, residing at Hamilton, in the county of Butler and State of Ohio, have invented a new, original, and ornamental Design for the Top Plate of an Amusement and Vending Device, of which the following is a specification, reference being had to the accompanying draw-

ing, forming part thereof, in which the figure is a perspective view of the top plate of an amusement and vending device, showing my new design.

I claim:—

The ornamental design for the top plate of an amusement and vending device as shown.

RAYBURN F. KENNEDY.
